OIL BURNER

Horace L. Douglas, New Britain, Conn.

Application July 28, 1932, Serial No. 625,371

2 Claims. (Cl. 158—87)

My invention relates to improvements in oil burners of the form having one or more combustion chambers that are defined by upstanding spaced tubes or cylinders of perforated material, and the object of my improvement is to produce an oil burner that is constructed and arranged so that under operating conditions there will be a relatively high degree of efficiency in the use of the fuel, in liquid form, that is delivered to the burner.

In the accompanying drawing:—

Figure 1 is a side elevation of my improved oil burner with the fuel inlet connection, the cylindrical combustion chamber wall structure being in part broken away.

Fig. 2 is a plan view of the same.

Fig. 3 is an enlarged sectional view on the line 3—3 of Fig. 2.

Fig. 4 is a view showing in separated condition the delivery tube and associated supporting structure.

Fig. 5 is a fragmentary plan view showing one of the inlets for fuel to the combustion chambers.

My improved oil burner comprises a combustion chamber structure that is composed of a set of annular chambers that are defined by cylindrical shells or wall structures made of perforated sheet metal, with provision for the admission of air on the two sides of the chambers.

As shown, there are two combustion chambers respectively the outer chamber 10 and the inner chamber 11. Said chambers project upwardly from annular channels that are provided in the main casing 12, and the shells 13 rest upon shoulders 14 that are provided on the walls 15 of said channels.

Said channels have generally closed bottoms that are interrupted by fuel duct openings. Thus the outer channel 16 is provided with a pair of inlet openings or passages 17 and the inner channel 18 is provided with a pair of inlet passages 19.

The delivery tube 20 is a relatively elongated tubular structure which terminates at the upper end in the emission opening 21 that is located substantially on the axis of the burner structure.

This opening 21 is located in appreciably spaced relation below the channels 16 and 18.

Thus there is an upward flow of vaporized fuel from the emission opening 21 to the combustion chambers 10 and 11, the flow being actually upward and outward in the structure shown, by reason of the axial location of the delivery tube

20. In the case of the fuel passages 17 and 19, these are substantially vertical, opening at their upper ends through the bottoms of the channels 16 and 18.

A chamber 22 is located in the space immediately below the channels 16 and 18 and communicating therewith through the passages 17 and 19 at its upper portion. The lower portion of said chamber 22 encloses the delivery tube 20, with the opposed enclosing wall portion in spaced relation thereto.

In the particular structure shown, the chamber 22 is of Y-shape, comprising a central vertical stem part and two divergent branches all merging at a junction substantially in the zone 15 of the emission opening 21 and communication with the passages 17 and 19 is effected through horizontal branches at the upper ends of the divergent branches.

Thus the divergent branches 23 merge laterally with the horizontal branches or extensions 24, which latter serve virtually as manifolds in effecting the delivery of the vaporized fuel.

The lower portion 25 of the chamber 22 constitutes the stem of the Y-shape, the interior border wall 26 thereof being separated from the tube 20 by the annular space 27.

The delivery tube 20 may be supported in any proper manner. As shown, the lower end thereof is screwed into the upper end of a sleeve 28 that is entered into the upper end 29 of a nipple 30 that closes the bottom of the vertical chamber extension or stem 25.

The fuel intake 31 is in the form of a right-angled structure that by its upwardly directed branch 32 is entered into the bottom end of the nipple 30.

The casing 12 is relatively massive and after being initially thoroughly heated serves to maintain the vaporization of the fuel before it is delivered from the tube 20. Vaporization is effected substantially as it is delivered from the tube 20 into the upper portion of the chamber 22 and thence thorough extensions 24 and passages 17 and 19 to the combustion chambers, the vaporized fuel being heated continually as it progresses upwardly and outwardly generally from the emission opening.

The isolation of the tube 20 from the adjacent and associated structure serves to facilitate the substantially complete combustion that is obtained, so that there is almost complete elimination of the deposit of carbon from the fuel under operating conditions.

As to size and the like, with two combustion chambers the provision of two arms or branches 23 in V-relation suffices for good results. With an increase in the number of combustion chambers additional arms or branches for the distribution are provided. Wicks may be housed in the channels 16 and 19.

In starting, the channels 16 and 18 will be flooded with liquid fuel that is ignited, resulting in heating the structures associated with the burning fuel, until the flooding material has been consumed down to the top of the delivery tube 20, the fuel supply being shut-off during the initial starting operation. Finally, the liquid fuel is again admitted and combustion is maintained by the use of fuel in vapor condition only, as it is admitted through the passages 17 and 19 to the combustion chambers 10 and 11.

The structure described comprises a fuel receiving portion at the lower end, a combustion portion at the upper end, and duct-like delivery means intermediate said portions and communicating therewith, the burner comprising furthermore adjacent the junction of said receiving portion and duct-like delivery means an open ended upstanding tube for the emission of fuel received by said lower portion, said tube being in spaced relation to any and all associated walls of the burner.

30 I claim as my invention:

1. An oil burner comprising a base having spaced concentric fuel grooves in the top surface thereof, perforated tubes upstanding above and

communicating with said grooves and forming combustion chambers thereabove, a chamber formed in said base and communicating with said grooves, a tube in said chamber having an open delivery end spaced from the walls of said chamber, means for delivering fuel to the other end of said tube, said tube serving to vaporize the fuel delivered thereto, said chamber formed in the base being of Y-form, the said tube being located in the stem thereof, with divergent branches projecting upwardly and outwardly from said stem serving to provide the communication of the chamber with the grooves. 5

2. An oil burner comprising a base having spaced concentric fuel grooves in the top surface 15 thereof, perforated tubes upstanding above and communicating with said grooves and forming combustion chambers thereabove, a chamber formed in said base and communicating with said grooves, a tube in said chamber having an open delivery end spaced from the walls of said chamber, means for delivering fuel to the other end of said tube, said tube being relatively of 20 small diameter and of elongated form with the adjacent spaced chamber walls of correspondingly elongated and tubular form, the chamber structure above said delivery end and tubular wall being in the form of upwardly and outwardly directed delivery conduits that by their upper ends serve to provide such communication, with said grooves. 25
